(57) CLAIM

(21) Appl. No.: 29/156,999

The ornamental design for a wall bar for advertisement cards or postcards, as shown and described.

(22) Filed: Mar. 15, 2002

DESCRIPTION

(30) Foreign Application Priority Data

Dec. 17, 2001 (WO) DM/199969001

FIG. 1 is a perspective view of the front side of a wall bar for advertisement cards or postcards according to the present invention;

(51) LOC (7) Cl. 06-04

FIG. 2 is a perspective view of the back side of the wall bar shown in FIG. 1;

(52) U.S. Cl. D6/571

FIG. 3 is a top view of the wall bar shown in FIG. 1;

(58) Field of Search D6/512-524, 552,

FIG. 4 is a bottom view of the wall bar shown in FIG. 1;

D6/566; 206/425; 211/13.1, 41.12, 42, 44,

FIG. 5 is a back view of the wall bar shown in FIG. 1;

45, 86.01, 87.01, 90.01, 90.03, 90.04, 106,

FIG. 6 is a front view of the wall bar shown in FIG. 1;

113, 119, 35, 134, 181.1; 248/302, 309.1,

FIG. 7 is a side view of the wall bar shown in FIG. 1; and,

317

FIG. 8 is an exploded view of the wall bar shown in FIG. 1.
